UNITED STATES PATENT OFFICE.

OSCAR A. ARNESON, OF CHICAGO, ILLINOIS.

DESIGN FOR A GASOLENE-LAMP.

No. 39,789.

Specification for Design.

Patented Jan. 26, 1909.

Application filed June 29, 1908. Serial No. 441,035. Term of patent 7 years.

To all whom it may concern:

Be it known that I, OSCAR A. ARNESON, a citizen of the United States, residing at Chicago, in the county of Cook and State of Illinois, have invented a new, original, and ornamental Design for Gasolene - Lamps, of which the following is a specification, reference being had to the accompanying drawing, forming part thereof.

The figure in the drawing is a side elevation of the gasolene lamp, showing my new design.

The salient feature of the lamp consists in the upper portion of the frame in which two straight diverging members connected together at their upper ends terminate with

parallel ends connected with the side fittings of the frame. The bottom portion of the frame is formed of two substantially parallel members having inwardly curved ends connected with the burner.

The drawing shows the lamp as constructed, on a reduced scale.

I claim—

The ornamental design for a gasolene lamp, as shown in the accompanying drawing and as described.

OSCAR A. ARNESON.
